Patented Dec. 13, 1921.

UNITED STATES PATENT OFFICE.

JAMES E. GROSJEAN, OF LIMA, OHIO.

SOLE FOR BOOTS AND SHOES.

1,399,766.

Specification of Letters Patent.

Patented Dec. 13, 1921.

Application filed July 17, 1919. Serial No. 311,497.

To all whom it may concern:

Be it known that I, JAMES E. GROSJEAN, a citizen of the United States, residing at Lima, in the county of Allen, State of Ohio, have invented certain new and useful Improvements in Soles for Boots and Shoes, of which the following is a specification.

This invention relates to soles for boots and shoes which are composed of fabric and rubber or rubber composition, and the soles shown and described are designed to replace leather soles. A sole of the general type of which this is an improvement is shown in Montgomery Reissue Patent No. 14,577, dated Dec. 24, 1918, and it is the object of this invention to improve upon this type of sole in certain respects as will appear as the description proceeds.

In the drawing:

Figure 1 is a plan view of a sole made in accordance with this invention.

Fig. 2 is a longitudinal cross section through the sole.

The improved sole of this invention comprises a backing or insole strip of fabric, or similar material indicated by the numeral 1 which backing forms a base or foundation for the entire sole, and preferably extends over the sole, except for a certain marginal area 2 which embraces the heel portion, the purpose of this area being to avoid the exposure of the edge of fabric about the heel of the finished shoe.

On this base or backing is built up the sole which comprises a tread portion 3 at the forward part of the sole, a shank portion 4^a and a heel portion 4. The tread portion may be of any preferred form and may be composed of alternate layers of fabric and rubber, the fabric being set on end in parallel rows as shown at 5, so that the fibers are presented endwise to the ground, the rows being separated by narrow strips of rubber, or rubber composition, 6. Other constructions of the tread portion may be substituted for this particular structure, it being practicable to replace the fabric and rubber in rows as shown with fabric and rubber arranged in any other design or with rubber and fibrous material ground up together. In place of the fibrous material mentioned, there may be substituted other ingredients such as ground cork or the like. The narrow separating strips of rubber may be of a composition similar to that referred

to above, and the fabric may be arranged in any preferred relationship, the parallel rows being shown as the preferred arrangement merely.

The heel 4 and shank portion 4^a of the sole is composed mainly of an insert 7 which may extend over part or the entire area of this portion of the sole. Ground cork may be used in combination with rubber as this gives an efficient substance for that portion of the sole and lightens it. Over this portion of the sole is extended a strip of fabric 8, which may be of one or more plies. The forward end of the fabric strip is bent downwardly at the instep as shown at 9 in Fig. 2 and extends for a short distance under the tread portion of the sole. The purpose of this construction is to closely unite or tie together the tread portion of the sole and the heel and shank portion and prevent separation or cracking at the point where these two parts meet, the strip 9 serving as a bond or link connecting and holding together the two dissimilar parts of the sole.

In the shank portion of the sole, it may be advisable to insert a stiff reinforcing plate 10 which is designed to distribute over a large area, the pressure of which frequently occurs in use at this point. This reinforcing strip or plate may be of any desired substance, preferably metallic, and may be of braided wire. When this strip is embedded in the sole as shown, constant pressure on a pedal or similar portion of machinery may be applied by the wearer of the shoe without tiring the foot.

Around the edge of the entire sole may be placed a finishing strip in the form of a rubber margin 11, which also may extend between and separate the tread portion and the shank of the sole. This margin is not essential and may be omitted if there is no objection against having the ends of the fabric strips show at the sides of the shoe.

It is obvious that changes and modifications may be made from the exact form shown, and the invention is not limited to such details as have been set forth but may be varied within the limits of the appended claims and within the scope of the invention.

I claim:

1. A sole for boots and shoes comprising a tread portion and a heel portion of differing compositions and a link between the

two said portions securely embedded in each and serving to reinforce the union of the two said portions.

2. A sole for boots and shoes comprising a tread portion and a heel portion, a flexible base extending over the upper side of said sole, the tread portion of said sole being composed of fibrous material and rubber, a layer of fabric on the under side of said heel portion inclosing the same and extending forward and embedded within the tread portion.

3. A sole for boots and shoes comprising a tread portion and a heel portion, a flexible base extending over the upper side of said sole, the tread portion of said sole being composed of fibrous material and rubber, a layer of fabric on the under side of said heel portion inclosing the same, and extending forward, crossing over at the instep and secured to the under side of the tread portion.

4. A shoe sole comprising a tread, a heel, and a shank portion, the first named portion being composed of fabric strips arranged endwise, the other portions being composed of a rubber composition, and a fabric strip joining the said portions being united to the heel and shank portions and

extended under and embedded in the tread portion.

5. A shoe sole comprising a tread, a heel, and a shank portion, the first named portion being composed of rubber and fabric strips arranged endwise, the other portions being composed of rubber and cork composition, a fabric strip joining the said portions extending over the top of the heel and shank portions and bent under and embedded in the tread portion, and a flexible base over the sole.

6. A flexible composition shoe sole having a reinforcing and stiffening plate embedded in the shank thereof, said plate being composed of braided wire.

7. A composition shoe sole having a tread, a heel and a shank portion, said portions each being composed in part of rubber, a flexible fabric strip extending from one portion to the other and embedded therein, and a metallic pressure plate embedded in the shank portion of the sole.

8. A flexible composition shoe sole having a reinforcing and stiffening plate embedded in the shank thereof, said plate being composed of woven wire.

JAMES E. GROSJEAN.
